UNITED STATES PATENT OFFICE.

HARLIE A. BLACKWELL AND FRANCIS P. MYERS, OF PORTLAND, OREGON.

DESIGN FOR A RADIATOR CAP.

60,309.

Specification for Design.

Patented Feb. 7, 1922.

Application filed August 30, 1921. Serial No. 497,067. Term of patent 3½ years.

To all whom it may concern:

Be it known that we, HARLIE A. BLACKWELL and FRANCIS P. MYERS, citizens of the United States, and residing at Portland, in the county of Multnomah and State of Oregon, have invented a new, original, and ornamental Design for Radiator Caps, of which the following is a specification, reference being had to the accompanying drawing, forming part thereof.

Fig. I is a plan view of our radiator cap.

Fig. II is a side view of Fig. I.

The wings are intended to be symbolical of chain-lightning.

The shading in the indentations represents red color.

We claim:

The ornamental design for a radiator cap as shown.

HARLIE A. BLACKWELL,
FRANCIS P. MYERS.
